(57) **CLAIM**

The ornamental design for a laparoscopic visualization device, as shown and described.

DESCRIPTION

FIG. 1 is a perspective view of a laparoscopic visualization device;

FIG. 2 is a bottom plan view thereof;

FIG. 3 is a top plan view thereof;

FIG. 4 is a front view thereof;

FIG. 5 is a rear view thereof;

FIG. 6 is a right side view thereof; and,

FIG. 7 is a left side view thereof.

The broken lines shown in FIGS. 1, 6, and 7 illustrate portions of the laparoscopic visualization device that form no part of the claimed design. The dash-dot lines shown in FIGS. 1, 3, and 4 illustrates a boundary line which forms no part of the claimed design.
